CLAIM

I claim the ornamental design for a charcoal burning stove, as shown and described.

DESCRIPTION

FIG. 1 is a three dimensional view of a first embodiment of a charcoal burning stove according to design;

FIG. 2 is a front view of the charcoal burning stove of FIG. 1; FIG. 3 is a rear view of the charcoal burning stove of FIG. 1; FIG. 4 is a top view of the charcoal burning stove of FIG. 1; FIG. 5 is a right side view of the charcoal burning stove of FIG. 1;

FIG. 6 left side of the charcoal burning stove of FIG. 1; FIG. 7 is a bottom view of the charcoal burning stove of FIG. 1;

FIG. 8 is a three dimensional view of a second embodiment of a charcoal burning stove according to my design; FIG. 9 is a front view of the charcoal burning stove of FIG. 8;

FIG. 10 is a rear view of the charcoal burning stove of FIG. 8; FIG. 11 is a top view of the charcoal burning stove of FIG. 8; FIG. 12 is a right side view of the charcoal burning stove of FIG. 8;

FIG. 13 is a left side of the charcoal burning stove of FIG. 8; and,

FIG. 14 is a bottom view of the charcoal burning stove of FIG. 8.

In FIGS. 7 and 14, details have been shown in broken lines since the bottom is not visible during normal use of the stove.
